ASSEMBLING TOOL

Francis J. Lenehan, Mountainside, N. J., assignor to Western Electric Company, Incorporated, New York, N. Y., a corporation of New York

Application September 5, 1941, Serial No. 409,606

4 Claims.

(Cl. 29—84)

This invention relates to assembling tools, and more particularly to tools for assembling split ring washers on fulcrum pins.

An object of the invention is to provide an assembling tool, particularly of the manually operable type, which is simple in construction and highly efficient in applying split ring washers on fulcrum pins.

With this and other objects in view, the invention comprises an assembling tool having a body made hollow to receive a ring holding magazine rod, the latter formed at its outer end to fit over an article, and a swingable arm supported by the body and having fingers formed to remove the first washer from the rod and move the washer onto the article.

Other objects and advantages will be apparent from the following detailed description taken in conjunction with the accompanying drawing, wherein

Fig. 1 is a front elevational view of the assembling tool, portions thereof being shown in section;

Fig. 2 is a side elevational view of the assembling tool illustrating the swingable arm in dotted lines in its normal position and in solid lines in its assembling position;

Fig. 3 is an enlarged fragmentary detailed view of the lower portion of the assembling tool, illustrating the assembling of a washer on an article, and

Fig. 4 is a fragmentary top plan view of portions of the tool.

Referring now to the drawing, the assembling tool illustrated therein may be termed a hand tool manually gripped and actuated to assemble split rings on articles. The tool has a body 10 of the general contour illustrated in Figs. 1 and 2, reduced at the lower end thereof, as indicated at 11, so that the operator may readily observe the operation being performed by the tool, the back portion of the body being reduced, as at 12, throughout the major portion of its length for the mounting of and actuation of a swingable arm 13. The body 10 is apertured throughout its length, providing hollow chambers 15 and 16. A magazine rod 17, to support a multiplicity of split ring washers 18, is disposed in the chamber 15 of the body, the lower end of the magazine rod being flared outwardly, as at 20, from a portion 21, where the lowermost washer 18 will rest supporting all the other washers above it, to a portion 22 which is equal or slightly larger in diameter than an article 23, such as a fulcrum pin, upon which a washer is to be disposed. The

extreme end of the magazine rod 17 is recessed, as at 24, for temporary interengagement of the rod with the article 23 and for automatic alignment thereof. As illustrated in Fig. 3, the article 23, namely the fulcrum pin, is grooved, at 26, to receive the washer, the latter functioning to secure a part (not shown) against displacement on the article.

Attention is now directed to the upper end of the magazine rod 17, which is pointed, as at 27, so that a quantity of the washers may be readily disposed thereon. The upper end of the magazine rod 17 extends into an aperture 30 of a support 31, a set screw 32 in the support serving to removably hold the magazine rod in assembled relation with the support. An aperture 33, through the adjacent wall of the body 10, provides access to the set screw for the removal of the magazine rod when it is desirable to replenish the washers. A vertical slot 34 is formed in the support 31 to receive an end 35 of a screw 36, serving to allow longitudinal movement of the body relative to the support and magazine rod yet maintain these parts against relative rotation. The support 31 is made hollow, at 38, to receive a spring 39 abutting against the inner wall of a cover 40 to normally urge the magazine rod outwardly to the position shown in Figs. 1 and 2. The cover 40 is internally threaded and disposed upon an externally threaded portion 41 of the body 10.

Referring now to the swingable arm 13, it will be observed that the upper portion of this arm is provided with an integral yoke 45, U-shaped in general contour, to straddle the body 10 adjacent flat portions 46, screws 47 extending into the body cooperating to provide a fulcrum for the swingable arm.

A spring 48, having its ends embedded in apertures in the body 10 and the arm 13, respectively, as illustrated in Fig. 2, normally urges the arm into the dotted line position shown in Fig. 2, which is the normal position for the arm.

The forward end of the arm 13 terminates at 50, this portion being of greater thickness than the remaining portion of the arm and having a lateral groove 51 therein. Companion fingers 52 have tongue portions 53 receivable in the groove 51 of the arm, this connection between the fingers and the arm permitting lateral movement of the fingers relative to each other and to the arm. An angle member 55, fixed to the arm 13 by screws 56, has a portion which extends beneath the fingers, providing a supporting table therefor. A dowel pin 57 is rigidly disposed in an aperture

of each finger and movable therewith a distance controlled by an elongate aperture 58 provided in the horizontal portion of the angle member 55 for each pin.

Attention is now directed to the contour of the fingers, particularly those portions extending forwardly from the arm 13. As illustrated in Figs. 1 and 2, the forwardly projected portions of the fingers gradually reduce in thickness to forward edges 60, which are almost knife-like, the under surfaces of each finger lying in a common horizontal plane, as indicated at 61, to maintain each washer, while being assembled, in a plane at right angles to the article upon which it is to be disposed. Attention is further directed to the fact that the inner or adjacent ends of the fingers are cut away, as at 62, to more easily straddle the magazine rod 17. As described, the fingers are movable outwardly away from each other, but springs 64 mounted upon the sides of the arm 13 engage the outer ends of the fingers to normally urge them toward each other.

The tool is conditioned for operation by filling the magazine rod with a supply of the washers 18, this being made possible by loosening the set screw 32 until the rod is free to drop out of the chamber 15 and free of the support 31. The washers may be readily disposed on the rod 17 over the pointed end 27 thereof, they being prevented from dropping off the opposite end of the rod due to the outwardly flared contour (20—22) thereof. The magazine rod may again be inserted in place and there held by the set screw 32. The operator may then move the tool in alignment with an article, such as the fulcrum pin 23, until the end of the article interengages the magazine rod 17 at the recess 24. At this time or prior to the movement of the tool into engagement with the article, the arm 13 may be swung about its pivot, namely the screws 47, against the force of the spring 48, moving the fingers 52 toward the magazine rod 17. During this movement the edges 60 of the fingers will pass between the bottom washer 18 and the remaining washers on the magazine, locating the washer to be assembled beneath the surfaces 61 of the fingers. At this time, assuming that the magazine rod 17 is disposed in engagement with the end of the fulcrum pin 23 and that the fulcrum pin is mounted against movement, the operator may move the body 10 and all other parts movable therewith, including the arm 13 and the fingers 52, toward the article, causing relative movement of the fingers and the magazine rod to move the first washer 18 over the portion 20, the portion 22 and onto the article. During this movement of the fingers 52 they will be caused to hug the rod 17 through the combined force of the springs 64, maintaining engagement with the selected washer and moving outwardly due to the varying contours of the portions 20 and 22, while the split washer is enlarged equal to or slightly greater than the diameter of the article so as to pass readily thereon as it leaves the portion 22.

During this operation there is relative movement of the magazine rod 17, its support 31 and the body 10. The extent of this movement is controlled by the cover 40 serving as a stop for the support 31. In the present instance the relative movement is such that the fingers 52 will not only remove the first washer from the supply and move the washer over the enlarged portions 20 and 22 of the magazine rod, but will continue

75 movement of the washer to the groove 26 in the article, where the resiliency of the washer will cause it to lie snugly in the groove.

It is, therefore, apparent that with this assembling tool split washers may be readily and accurately assembled on articles with little effort, the assembling tool requiring two main movements on the part of the operator to accomplish this result, one being the gripping of the tool 10 to bring about movement of the arm 13 relative to the body to remove the first washer from the supply and then move the tool while in this condition with the first washer already selected, this latter movement including the movement of the tool into registration with the article and the continued movement of the body 10, the arm 13 and the fingers 52, while the magazine rod 17 stops with its engagement with the article, causing functioning of the fingers to move the selected washer over the tapered or enlarging surfaces 20 and 22 of the rod, conditioning the washer to be moved onto the article and continuing this movement until the washer drops into the groove 26.

The embodiment of the invention herein disclosed is merely illustrative and may be widely modified and departed from in many ways without departing from the spirit and scope of the invention as pointed out in and limited solely by the appended claims.

What is claimed is:

1. An assembling tool comprising a magazine rod, for a supply of split rings, having an end formed for interengagement with an end of a cylindrical article and adapted to cause alignment of the axes of the article and rod, a hollow support for the rod, means for movement of the support relative to the rod between a normal position and an assembling position, an arm mounted on the support for swinging movement into and out of an assembling position, and fingers supported by a free end of the arm for movement relative to each other and the arm to straddle the rod and pass between the first and second ring thereon and to move the first ring onto the article during movement of the support into the assembling position.

2. An assembling tool comprising a magazine rod, for a supply of split rings, having an end formed for interengagement with an end of a cylindrical article and adapted to cause alignment of the axes of the article and rod, a hollow support for the rod, means for movement of the support relative to the rod between a normal position and an assembling position, an arm mounted on the support for swinging movement into and out of an assembling position, fingers supported by a free end of the arm for movement relative to each other and the arm to straddle the rod and pass between the first and second ring thereon and to move the first ring onto the article during movement of the support into the assembling position, and means supported by the arm and adapted to urge the fingers toward each other.

3. An assembling tool comprising a magazine rod, for a supply of split rings, having an end formed for interengagement with an end of a cylindrical article and adapted to cause alignment of the axes of the article and rod, a hollow support for the rod, means for movement of the support relative to the rod between a normal position and an assembling position, an arm mounted on the support for swinging movement into and out of an assembling position, fingers

supported by a free end of the arm for movement relative to each other and the arm to straddle the rod and pass between the first and second ring thereon and to move the first ring onto the article during movement of the support into the assembling position, and means to normally urge the arm out of assembling position.

4. An assembling tool comprising a magazine rod, for a supply of split rings, having an end formed for interengagement with an end of a cylindrical article and adapted to cause alignment of the axes of the article and rod, a hollow support for the rod, means for movement of the

support relative to the rod between a normal position and an assembling position, an arm mounted on the support for swinging movement into and out of an assembling position, and fingers supported by a free end of the arm for movement relative to each other and the arm to straddle the rod and pass between the first and second ring thereon and to move the first ring onto the article during movement of the support into the assembling position, the said interengaging end of the rod causing spreading of the ring to pass over the aligned article.
